UNITED STATES PATENT OFFICE.

WILLIAM C. HEDGCOCK, OF CHICAGO, ILLINOIS, AND LOREN L. WHITNEY, OF HAMMOND, INDIANA, ASSIGNEES TO AMERICAN STEEL FOUNDRIES, OF CHICAGO, ILLINOIS, A CORPORATION OF NEW JERSEY.

BRAKE-BEAM FULCRUM.

Application filed October 23, 1924. Serial No. 745,295.

This invention relates to a brake-beam fulcrum.

One object of the invention is to provide a bar of metal to be made into a brake-beam fulcrum and which in bar form is properly shaped to facilitate the making of a brake-beam fulcrum without the necessity of the usual upsetting of the metal to form various parts of a brake-beam fulcrum.

10 This and other objects are accomplished by means of the arrangement disclosed on the accompanying sheet of drawings, in which

15 Fig. 1 is a top plan view of a finished brake-beam fulcrum embodying our invention,

Fig. 2 is a top plan view of a bar of metal or a blank from which the brake-beam fulcrum is made,

20 Fig. 3 is a side elevation of the same,

Fig. 4 is an enlarged sectional view taken in the plane of line 4—4 of Fig. 2,

Fig. 5 is an enlarged sectional view taken in the plane of line 5—5 of Fig. 2,

25 Fig. 6 is a sectional view taken in the plane of line 6—6 of Fig. 2, and

Fig. 7 is a top plan view of a continuous bar from which the section shown in Fig. 2 is cut.

30 The various novel features of the invention will be apparent from the following description and drawings and will be particularly pointed out in the appended claims.

Referring to the figures of the drawings, 35 and more particularly first to Fig. 1 of the drawings, it will be noted that the fulcrum 10 is integrally formed and has two spaced legs 11 between which a brake lever (not shown) is pivotally mounted by a pivot pin 12 (not shown) extending through openings 13 in the legs 11. One end of the fulcrum member is provided with a tension rod seat 14, while the other end has oppositely extending feet 15 for attachment to the brake-beam compression member.

45 In the manufacture of brake-beam fulcrums an excess amount of material usually is accumulated at one end of the fulcrum for the purpose of providing a proper tension rod seat. Usually this is done by an upsetting method, such upsetting method involving additional steps, which in turn increases the cost of the final product. Likewise additional expense is incurred by pro-

viding enlarged upset portions or bosses in 55 the legs 11 for providing pivot pin holes which have sufficient bearing area.

To overcome the various upsetting steps and to reduce generally the cost of manufacture of brake-beam fulcrums, and at the same time to provide a simple and durable fulcrum adapted to meet the various requirements under service conditions, I have provided a bar, as shown in Figs. 2 to 6 inclusive, from which the fulcrum can be easily, 60 quickly, and cheaply made. This bar is variable in thickness, the end portions 15 being of less thickness than the intermediate or elongated central portion 16. It might be said that the central portion of the bar, 65 or that portion of the bar intermediate the end portions, has an enlargement in the nature of a boss. The blank or bar, as shown in Figs. 2 to 6 inclusive, after being heated and having its ends shaped and twisted, is 70 bent at its middle portion so that a relatively thick bent end portion is provided, in which the tension rod seat may be formed without upsetting the metal at that point. Likewise the metal at the pin holes 12 is relatively 75 thick so that the bearing surface provided in said holes is relatively great, and such bearing surface is provided without first upsetting the metal at such points.

80 It is seen, therefore, that a relatively strong, simple, and efficient brake-beam fulcrum is provided from a single blank or bar which has a central enlargement which provides sufficient metal to form a tension rod seat and lever pivot pin holes of sufficient bearing area without upsetting the metal at such points. The bar as shown in Fig. 2 is preferably a rolled bar and is cut from a larger bar 17 rolled and shaped as shown in Fig. 7.

95 We claim:

1. A blank from which a brake-beam fulcrum may be made, comprising a bar of predetermined thickness having an elongated enlargement extending throughout the range 100 of the possible location of the bearing openings.

2. A blank from which a brake-beam fulcrum may be made, comprising a bar of predetermined thickness having an elongated 105 enlargement extending throughout the range of the possible location of the bearing holes in both legs and the space therebetween to

form a single and continuous portion of increased metal.

3. A blank from which a brake-beam fulcrum may be made, comprising a metal bar of predetermined thickness, and having an elongated enlargement providing stock of increased thickness for forming bearings, by holes selectively located throughout the length of said enlargement.

10 4. A brake-beam fulcrum having a metal

body portion of predetermined thickness, and enlargements on the legs thereof providing portions of increased thickness along its length throughout the range of the possible location of the bearing holes. 15

Signed at Chicago, Illinois, this 20th day of October, 1924.

WILLIAM C. HEDGCOCK.
LOREN L. WHITNEY.
